ATTORNEY

UNITED STATES PATENT OFFICE.

RALPH EHRENFIELD, OF EAST PITTSBURGH, PENNSYLVANIA, ASSIGNOR TO WESTINGHOUSE ELECTRIC & MANUFACTURING COMPANY, A CORPORATION OF PENNSYLVANIA.

MOUNTING FOR SEWING-MACHINE MOTORS.

Application filed March 14, 1921. Serial No. 452,069.

To all whom it may concern:

Be it known that I, RALPH EHRENFIELD, a citizen of the United States, and a resident of East Pittsburgh, in the county of 5 Allegheny and State of Pennsylvania, have invented a new and useful Improvement in Mountings for Sewing-Machine Motors, of which the following is a specification.

My invention relates to machines, such as 10 sewing machines, that are equipped for operation by electric motors, and it has for its object to provide a structure wherein the machine and the motor are united in an improved manner to form a strong, rugged, 15 compact and inexpensive combination.

Briefly, my invention comprises mounting the motor on a support disposed adjacent to, or mounted on, the head of the sewing machine.

20 Heretofore, it has been customary to drive a sewing machine by means of a motor so disposed on the machine table as to engage the hand wheel or by fastening the motor to the sewing machine frame by means of a 25 complicated and expensive supporting structure.

More specifically, my invention comprises 30 pivotally mounting the motor upon an auxiliary casing member mounted adjacent to, or on the head of, the sewing machine and disposing a resilient means between the head of the sewing machine and the auxiliary casing member that is adapted to yieldingly hold the driving pinion of the motor in engagement with the hand wheel of the sewing machine.

For a better understanding of my invention, reference may now be had to the accompanying drawings in which—

40 Fig. 1 is a side elevational view of a portion of a sewing machine provided with a motor constructed in accordance with my invention.

Fig. 2 is a cross-sectional view of the 45 structure illustrated in Fig. 1, the section being taken along the lines II—II thereof.

Fig. 3 is an elevational view of a motor 50 employed in connection with my invention, this view showing that side of the motor which is disposed within the casing when the motor is in its operative position.

Fig. 4 is an elevational view of a portion 55 of the auxiliary casing, with the motor removed therefrom.

In the drawings, a sewing machine 5 is

shown as provided with the usual shaft 6 and hand wheel 7. The head 5 comprises a substantially horizontally extending arm 8, parts of which are broken away, and an upright standard 9, one side portion 9a of which is indented, as is best shown in Fig. 2. Attached to one side of the upright standard 9 is an auxiliary casing member 10 provided with a substantially circular opening 11 therein. The casing member 10 is 60 attached to the upright standard 9 by means of a plurality of bolts 12, or any other suitable attaching means.

An electric motor 13, provided with a shaft 14 and a driving wheel 15, is mounted in the opening 11 in such manner that the driving wheel 15 operatively engages the hand wheel 7 of the sewing machine. The motor 13 is provided with a flange 16 having a peripheral machined surface which 70 is adapted to engage that portion of the casing member 10 immediately adjacent to the opening 11 therein. The motor is also provided with diametrically oppositely disposed lugs 17, as best shown in Fig. 3, 75 which are adapted to co-operate with co-acting substantially semi-circular lugs 18 in the opening 11 of the casing member 10, as best shown in Fig. 4.

A leaf spring 19 is attached, at its central portion, to the motor 13 in such manner that the ends thereof project to engage the lugs 18 of the casing member 10 to aid the lugs 17 in holding the motor 13 in its operative position with respect to the opening 11. This spring serves to prevent vibration of the motor with respect to the machine head. The motor 13 is provided with a lug 20 which is normally disposed within the space between the upright standard and the casing 10 and engages a coiled spring 21, also disposed therein, which biases the motor to its operative position and thus yieldingly maintains engagement between the driving wheel 15 and the hand wheel 7.

In order to attach the motor to the sewing machine head, the motor may be inserted in the opening 11 and revolved against the force of the spring 21 until the wheel 15 reaches a position below the hand wheel 7. The casing member 10 is then attached to the upright standard 9 by means of the bolts 12, after removing the hand wheel 7. If the casing is already attached to the upright standard, the motor may be attached 100

by first removing the hand wheel 7, turning the motor into such a position that the lugs 17 and the ends of the leaf spring 19 may be passed axially through the openings between the lugs 18 in the casing 10. The motor is then so turned that the lugs 17 and the ends of the spring 19 engage the lugs 18, with the spring 21 compressed and the driving wheel 15 disposed below its normal operative position. The hand wheel 7 may then be mounted upon the shaft 6, and the motor 13 be released, whereupon the spring 21 will bias the motor to actuate the wheel 15 into operative engagement with the hand wheel 7.

It will be noted that the motor and the spring 21 are disposed within the recess caused by indenting the portion 10 of the upright standard 9, thereby reducing the overall width of the machine.

While I have shown but one form of my invention and have described in detail but a single application of the same, it will be obvious to those skilled in the art, that it is not so limited but is susceptible of various minor modifications and changes without departing from the spirit thereof, and I desire, therefore, that only such limitations shall be placed thereupon as are imposed by the prior art, or are specifically set forth in the appended claims.

I claim as my invention:

1. In combination, a sewing-machine head comprising an upright standard, an auxiliary casing member mounted adjacent to said upright standard and provided with an opening therein and an electric motor mounted at least partially within said opening.

2. In combination, a sewing-machine head comprising an upright standard, an auxiliary casing member mounted adjacent to said upright standard and provided with an opening therein and an electric motor pivotally mounted at least partially within said opening.

3. In combination, a sewing-machine head comprising an upright standard having a shaft and a hand wheel mounted thereon, an auxiliary casing member mounted adjacent to said upright standard and provided with an element of a bayonet joint, an electric motor adapted to be mounted on said casing member and provided with a co-operating bayonet joint element and means for operatively connecting said motor to said hand wheel.

4. A sewing-machine having a head comprising an upright standard having a hand wheel mounted thereon, an auxiliary casing member mounted adjacent to said head, a rotatably adjustable electric motor removably attached to said head and provided with a driving wheel and means for moving said motor upon its pivotal axis to effect en-

gagement of said driving wheel with said drive wheel.

5. A sewing machine having a head comprising an upright standard having a hand wheel mounted thereon, an auxiliary casing member mounted adjacent to said head and provided with an opening therein, an electric motor mounted in proximity to said opening and having projections that effect supporting engagement with the wall thereof and provided with a driving wheel and means for yieldingly holding said driving wheel in engagement with said hand wheel.

6. A sewing machine having a head comprising an upright standard having a hand wheel mounted thereon, an auxiliary casing member mounted adjacent to said head and provided with a substantially circular opening having lugs projecting thereinto, an electric motor provided with a driving wheel and having lugs adapted to coact with said first mentioned lugs to hold said motor into position and means for yieldingly holding said driving wheel in engagement with said hand wheel.

7. A sewing-machine having a head comprising an upright standard having a hand wheel mounted thereon, an auxiliary casing member mounted adjacent to said head and provided with a substantially circular opening having lugs projecting thereinto, an electric motor provided with a driving wheel and having lugs adapted to coact with said first mentioned lugs to hold said motor in position and a spring interposed between said head and said motor to hold said driving wheel in engagement with said hand wheel.

8. In combination, a sewing machine head comprising an upright standard having a shaft and a hand wheel mounted thereon, an auxiliary casing member mounted adjacent to said upright standard and provided with an element of a bayonet joint, an electric motor having a driving wheel adapted to engage said hand wheel and provided with a bayonet-joint element adapted to co-operate with the element on said head and means for yieldingly holding said driving wheel in engagement with said hand wheel, the axis of said co-operating bayonet-joint elements extending through approximately the center of gravity of the motor.

9. A sewing machine having a head comprising an upright standard having a hand wheel mounted thereon, an auxiliary casing member mounted adjacent to said head and provided with an opening having inwardly projecting lugs, an electric motor mounted adjacent to said opening and resilient means interposed between said motor and said lugs to hold said motor in position.

10. A sewing machine having a head comprising an upright standard having a hand wheel mounted thereon, an auxiliary casing member mounted adjacent to said head and

provided with an opening having inwardly projecting lugs, an electric motor mounted adjacent to said opening and a leaf spring having its intermediate portions attached to 5 said motor and having its ends adapted to coact with said lugs to hold said motor in position.

11. A sewing machine having a head comprising an upright standard having a hand 10 wheel mounted thereon, an auxiliary casing member mounted adjacent to said head and provided with an opening having inwardly projecting lugs, an electric motor provided with a drive wheel and having lugs adapted 15 to coact with said first mentioned lugs to hold said motor in position, resilient means interposed between said motor and said machine head to further aid in positioning said motor and means for yieldingly holding said

drive wheel and said hand wheel in engagement. 20

12. In combination, a sewing machine head having a hand wheel mounted thereon and comprising an upright standard, an auxiliary casing member mounted adjacent 25 and attached to said upright standard, said casing member being provided with an opening therein, an electric motor provided with a driving wheel pivotally mounted within said opening and a spring disposed between said upright standard and said casing member and adapted to cause 30 said driving wheel to yieldingly engage said hand wheel.

In testimony whereof I have hereunto subscribed my name this 7th day of March, 35 1921.

RALPH EHRENFELD.
